DESIGN FOR A COAT

Samuel H. Dick, New York, N. Y.

Application June 20, 1938, Serial No. 77,945

Term of patent 3½ years

To all whom it may concern:

Be it known that I, Samuel H. Dick, a citizen of the United States and residing in Manhattan, in the city, county, and State of New York, have invented a new, original, and ornamental Design for a Coat, of which the following is a specification, reference being had to the accompanying drawing, forming part thereof.

Fig. 1 is a front view of a coat showing my new design.

Fig. 2 is a rear view thereof.

I claim:

The ornamental design for a coat substantially as shown.

SAMUEL H. DICK.
